CLAIM

The ornamental design for a box for light bulbs, as shown as described.

DESCRIPTION

FIG. 1 is a front perspective view of a box for light bulbs showing my new design;

FIG. 2 is a front elevation view of the box of FIG. 1; FIG. 3 is a rear elevation view of the box of FIG. 1; FIG. 4 is a right side elevation view of the box of FIG. 1; FIG. 5 is a left side elevation view of the box of FIG. 1; FIG. 6 is a top plan view of the box of FIG. 1; and, FIG. 7 bottom plan view of the box of FIG. 1. The dashed broken lines illustrate portions of the box for light bulbs and form no part of the claimed design.
